JOHN N. REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

AUTOMATIC SWITCHING APPARATUS FOR TELEPHONE-EXCHANGE SYSTEMS.

1,383,756.

Specification of Letters Patent.

Patented July 5, 1921.

Application filed August 1, 1917. Serial No. 184,000.

To all whom it may concern:

Be it known that I, JOHN NEWBERRY REYNOLDS, a citizen of the United States, residing at Greenwich, in the county of Fairfield and State of Connecticut, have invented certain new and useful Improvements in Automatic Switching Apparatus for Telephone-Exchange Systems, of which the following is a full, clear, concise, and exact description.

10 This invention relates to automatic switching apparatus for telephone exchange systems, and is a modification of the switch shown and described in an application to the same inventor, Serial No. 158,190, filed March 15 29th, 1917.

In said application, Serial No. 158,190 filed March 29th, 1917, there is shown and described a switch in which there are a plurality of unit layers of multiple contacts 20 mounted in superimposed relation to each other, and brushes, each adapted to be selectively moved to the layers and transversely to the contacts of a selected layer. Only two electromagnets are used in the operation of the switch, one for stepping the brushes, the other for controlling the change-over from one character of stepping to the other and for controlling the release of the switch.

30 While a switch made in accordance with the invention of said application Serial No. 158,190 has its advantages from an operative and cost standpoint, it requires a departure from the standard form of circuits for such switches to adapt it to the present systems of operation. It is the object of this invention to provide a switch operating on the principles above outlined, which may be readily adapted to existing circuits with but slight 35 change in the wiring.

In accordance with the general features of this invention the switch of the earlier application is modified to include a third magnet which is used for releasing the brushes at 40 the termination of a connection.

In the drawings illustrating the invention, Figure 1 is a view in side elevation of a brush operating mechanism embodying features of this invention; Fig. 2 is a detail sectional

view taken upon the line 2—2 of Fig. 1; Fig. 50 3 is a sectional view taken upon the line 3—3 of Fig. 1; Fig. 4 is a perspective view of a part of the brush operating mechanism; and Fig. 5 is a view showing the manner in which the apparatus embodying the features of 55 this invention may be wired in a system.

Referring first to Fig. 1, the reference numerals 5, 5 designate a plurality of multiple contact strips. Each of the multiple contact strips 5, 5 is the same as illustrated in co-pending application of the same inventor Serial No. 130,348, filed November 9, 1916, and consists in general of a plurality of longitudinally extending conductors insulated from each other and divided into sets. 60 Each conductor of each set has a plurality of brush contacting surfaces thereon, the contacting surfaces of adjacent conductors of the same set being longitudinally separated from each other and the contacting 65 surfaces of corresponding conductors of the several sets being in the same transverse line of the strip.

The brush operating mechanism, which is illustrated in detail in Figs. 1 to 4 inclusive, is designed to move the brushes step-by-step to the several levels of multiple contact strips 5, 5 and transversely thereof to selected contacts of a strip. As shown in the drawings, 6, 6 designate brushes mounted 75 upon a carriage 7 which is secured to a shaft 8. The shaft 8 is secured to a frame plate 9 by members 11 and 11'. Located adjacent to the shaft 8 is a toothed bar 12 adapted to be engaged by a stepping pawl 14 carried by an 80 armature 15 of a stepping magnet 20. The toothed bar is supported by collars 21 and 22 which are slidably upon the shaft 8. Also 85 slidably mounted upon the shaft 8 is a notched bar 24 with an extension 25 adapted 90 to engage a notch 26 in the toothed bar 12 so as to lock the two bars together in the normal position of the switch.

In the first movement of the apparatus in response to impulses through the stepping 95 magnet 20, the pawl 14 will engage the toothed bar 12 to move said bar 12 and the notched bar 24 upwardly in steps equal in

length to the distance between two successive teeth on said bar 12. Each of these steps will be equal to the vertical distance between adjacent multiple contact layers and will 5 continue until the brushes 6, 6 have been moved into a position opposite a desired layer. At the cessation of the first series of impulses through the stepping magnet 20 a side switch magnet 30 will be caused to operate. This magnet by its armature 49 controls the operation of a side switch and the movement of the levers 46 and 50. The function of the side switch is to prepare circuits at the proper times for the control of 10 the automatic switch. An arm 35 of the side switch carries a set of brushes 36 adapted to wipe over a series of contacts 37 arranged in the arc of a circle. The arm is held under tension by a spring 38. The arm 35 is released step by step under the influence of 15 spring 38 by an escapement mechanism controlled by the armature 49 of the magnet 30. This escapement mechanism consists of a member 40, notched on both sides and fixed 20 to the arm 35, and a pair of arms 41 and 42 pivoted on the armature pivot pin 43. These two arms tend to move together under the influence of a spring 44. The arm 35 also carries a cam 45 to control the movement of the 25 lever 46 pivoted at 47 and normally under the tension of spring 48.

In the normal position of the side switch the arm 42 is in engagement with the first tooth on the right-hand side of the member 30 as shown. In this position the brushes are 35 in contact with the first set of contacts of the bank 37, and the cam 45 positions the lever 46 to hold the arm 79 of lever 50 pivoted at 52 which is normally under tension 40 of spring 51, in engagement with the arm 10 of lever 46. The teeth on the member 40 of the side switch are so arranged as to cause the brush set 36 to advance one step upon the retractive movement of the armature 49.

45 After the cessation of the first set of impulses through the magnet 20 by means of which the brushes 6, 6, were raised to the desired level, there will be an operation of the armature of the magnet 30 to cause the side switch to be advanced one step by the arms 41 and 42. This first step of the side switch causes the movement of the lever 46 by the roller 58 pressing against the cam 45. This movement of the lever 46 causes an arm 50 59 thereon to move the extension 25 of notched bar 24, normally tensioned by spring 20, out of engagement with the notch 26 of the toothed bar 12, and the notched bar 24 into engagement with the latch piece 29. This releases the toothed bar 12 from 55 the notched bar 24, locking the latter, however, against movement, so that subsequent operations of the stepping magnet 20 will advance only the toothed bar 12. When the lever 46 is moved to the left by the roller 58

pressing against the cam 45 it releases the lever 50 which was engaged therewith through an arm 10 of said lever 46.

Now the first one of the succeeding impulses through the stepping magnet 20 will cause the toothed bar 12 to be raised a distance equal to the distance between two successive teeth, but immediately after it is raised the extension 62 of the lever 50 will be swung around the pivot 52 until it engages with the stop 61, thereby limiting the downward movement of the armature 15 to one half of the distance of its downward movement before. The first long step of the toothed bar 12 will operate a bell-crank lever 70 70 to move the brush carriage 7 in a direction at right angles to the shaft 8 and through a distance equal to the distance between two successive teeth on the bar 12. This first step of the brush carriage is sufficient to bring the brushes 6, 6 into engagement with contacts in the first row of the selected strip 5. The succeeding steps of the bar, however, in response to impulses through the magnet 20, due to the extension 75 62 of the lever 50 being moved about the pivot 52 to higher position so as to engage the stop 61 and rest on the under edge of the armature 15, will only be half the distance of the impulses of the first series and 80 the first impulse of the second series, so that the subsequent movement of the brushes 6, 6 will be only the distance between successive sets of contact surfaces. A sufficient number of current impulses of the second series 85 will be sent to move the brushes 6, 6 into engagement with a selected set of terminals in the strip selected by the first set of impulses. Upon the cessation of the second series of impulses the armature of the magnet 30 will again be operated to cause the movement of the side switch one step further. The moving of the side switch to the third set of contacts has no further effect upon the positions of the brush-operating 90 parts but may prepare the circuit for ringing the called subscriber's line. At the end of the ringing a third energization of the magnet 30 may take place to move the wipers 36 into the fourth position and to 95 move the arm 77 of the armature of the release magnet 74 into engagement with the lug 16 of the member 40 and the other arm 19 into engagement with the lower end of the lever 50 and the extension 71 of the 100 plate 72.

105 The moving of the side switch into the fourth position has no further effect on the position of the brush operating mechanism. The parts will remain in the position with the wipers in the fourth position during the conversational period, at the end of which time the operation of disconnection will cause energization of the magnet 74. Energization of magnet 74 causes the arm 19 of 110

the armature of the magnet 74 to engage an extension 71 of the pivotal plate 72, which carries a pawl 75 normally adapted to engage the teeth of the toothed bar 12 to retain it in its elevated position. The engaging of arm 19 with the extension 71 of the plate 72 causes the latter to be turned about its axis, throwing the pawl 75 out of engagement with the toothed plate 12. This will 10 cause the toothed plate 12 to drop by gravity and cause the brush carriage 7 to move outwardly, assisted by a spring 76, to draw the brushes 6, 6 clear of the contact strips 5, 5.

At the instant of energization of magnet 15 74, the arm 77 of the armature of magnet 74 also engages a projecting lug 16 on the member 40. This with assistance of the spring 38 swings the wipers back into normal position, allowing the lever 46 to assume 20 its normal position aided by the spring 48. The arm 19 of the armature of release magnet 74 is of sufficient width to engage the lower end of lever 50 so that when toothed plate 72 is turned about its pivot the lever 50 25 is also thrown out of engagement with the stop 61 and the extension 79 is again held by the arm 10 of the lever 46. When the toothed plate 12 has dropped far enough to permit extension 25 to engage notch 26, 30 notched bar 24 is also released from latch piece 61, it having been previously prepared for return to normal by extension 59 being moved from contact therewith, and both plates drop together to normal position. 35 The switch is then ready for the next operation.

In Fig. 5 the switch mechanism of this invention is shown connected in a circuit to function as a selector, although it is obvious 40 that the device is not limited to this specific use.

Referring to Fig. 5, A may represent a calling subscriber's station, the line for which is connected with line switch terminals 45 111, 111 adapted to be engaged by movable contacts 112, 112. Assuming that the subscriber at A desires connection with a subscriber, say at a substation B, the operation will be as follows: The subscriber A, upon 50 removal of his receiver from the switchhook will automatically have his line connected with the movable contacts 112, 112 in a well known way through the operation of a line switch. Following the closure of the line 55 switch contacts, a relay 115 will be energized over the line circuit through position 1 of side-switch wipers 116, 117, controlled by a selector switch 120, embodying the features of this invention. The energization of relay 115 will cause it to open its back contact 121, and close its front contact 122 to ground, thereby completing a parallel circuit, one limb including a slow release relay 123, the other limb including a test relay 124, the 60 latter circuit including a side-switch wiper

125 in its first position. Upon energization the test relay becomes locked up over a circuit including its own contact, side-switch wiper 126 in its first and second positions and a horizontal off-normal contact 127 of 70 the selector 120. The slow release relay 123 upon energization opens back contact 128 and closes front contacts 129 and 130. After removing his receiver from the hook, the subscriber A will operate his dial in the 75

usual manner to send the requisite number of impulses to move the brushes 6, 6 into position to engage contacts in the level with which switching apparatus associated with the subscriber B may be connected. In the 80 particular instance we will assume that contacts in the fourth level of the contact strip 5, 5 are sought, in which case four impulses will be sent from station A. These impulses open the circuit of the relay 115 to cause it 85 to intermittently close its back contact 121 which completes a circuit for slow release magnet 131 in series with the stepping magnet 20 of the selector switch 120, which circuit includes side-switch wiper 132 in its 90 first position. Relay 131, in pulling up, closes its contact 133 to complete a circuit from ground through side-switch wiper 134 and the side-switch magnet 30. The relays 123 and 131 both being slow release 95 will hold up during the sending of impulses, The stepping magnet 20, however, will respond to the impulses resulting from the opening and closing of the contact 121 to step the toothed bar 12 and with it the notched 100 bar 24 and brushes 6, 6 upwardly in steps of a length equal to the vertical separation of the layers 5, 5. At the end of the fourth step or impulse from the station A, the relay 115 will remain energized and open the circuit 105 of the relay 131 at contact 121, causing it to drop back and open the circuit of the side-switch magnet 30 at the contact 133. The armature 49 of the side-switch magnet 30, in releasing, steps the side-switch wipers 110 from their first to their second position. The movement of the side-switch wipers from their first to their second position, swings the lever 46 about its pivot 47, releasing lever 50, unlocks toothed bar 12 from notched bar 115 24, and locks notched bar 24 against movement by means of latch piece 29. Also it places the extension 62 of lever 50 in position so that the extension will be moved into engagement with stop 61 and under the armature 15 of stepping magnet 20. As soon as the side-switch wiper 36 is moved from its first to its second position a circuit will be completed for the stepping magnet 20 120 which may be traced from ground through 125 a front contact 136 of test relay 124, armature 15 of stepping magnet 20, contact 137 on said armature, side-switch wiper 132 in its second position and through the magnet 20 to battery. This circuit will exist so long 130

as the relay 124 is retained energized. Upon the first horizontal step of the brushes 6, 6 however, the bell crank lever 70 rotates about its pivot and the horizontal off-normal contact 127 will be opened to transfer the holding circuit of relay 124 to the shortest brush 6 of the set which constitutes the test brush. The first horizontal step of the brushes 6, 6 will be a long one, as hereinbefore described, 10 and will bring said brushes into engagement with the first set of contacts 2, 3 and 4 of the layer. If any of the contacts of this set have been taken for use by another switch, there will be a ground on the contacts 4, 15 which will hold the relay 124 energized until the stepping magnet 20 has made another step. This stepping operation will be continued until the brushes 6, 6 land on a set of contacts, the contact 4 of which is not 20 grounded. When this occurs, the circuit for the test magnet 124 will be opened, which will cause it to open the stepping magnet circuit. At the time that the side-switch wipers moved from their first to their second 25 position, the wiper 134 completed an energizing circuit for the side-switch magnet 30 from a front contact 137 on the relay 124, which caused it to draw up its armature 49. As soon as the relay 124 becomes deenergized 30 by reason of the brushes 6, 6 landing on idle contacts, this last traced circuit will be opened and the armature 49 will release to move all of the side-switch wipers from their second to their third position. 35 In their third positions, the wipers 116, 117 connect the circuit of station A with conductors 140, 141 leading to the longest and middle brushes 6, 6. This connection includes contacts 142, 142 of a relay 143 40 which is energized over a circuit including the front contact 129 of the relay 123. The relay 115 is retained in bridge of the line of station A and so remains until the completion of the conversation and the subscriber A hangs up his receiver to break the 45 circuit of his line. When this occurs relay 115 releases, opening the circuit of relay 123 at contact 122, causing said relay 123 to release to close its back contact 128. The closure of contact 128 completes an energizing 50 circuit for the side-switch magnet 30 which includes a side-switch wiper 145 in its third position, an interrupting contact 149 on the armature 49 of the side-switch magnet 30, 55 the winding of side-switch magnet 30 and battery. This causes the side-switch magnet 30 to pull up and release its armature to step the wipers into their fourth position. In the fourth position of the side-switch 60 wiper 145 release magnet 74 is energized over ground, back contact 128 of relay 123, side-switch wiper 145 in its fourth position, winding of release magnet 74 to battery. When the armature of release magnet 74 65 pulls up, arm 77 engages lug 16 on member

40 and arm 19 engages extension 71 of pivoted plate 72, and lower end of lever 50, causing the side-switch wipers to be returned to normal position and toothed plate 12 and notched plate 24 to be released and returned 70 to normal, as hereinbefore described.

What is claimed is:

1. In an automatic switch, stationary contacts, a movable contact member, a stepping pawl for moving said contact member in two 75 distinctly separate movements in different directions to engage said stationary contacts, means for operating said pawl, means for holding said movable contact in advanced position, and a release magnet for releasing 80 said holding means to restore the movable contact to its normal position.

2. In an automatic switch, stationary contacts, a movable contact member, a stepping pawl for moving said contact member in two 85 distinctly separate movements in different directions to engage said stationary contacts, a holding pawl for holding said movable contact in advanced position, and an electromagnet for releasing said holding pawl to 90 restore said movable contact member to normal position.

3. In an automatic switch, stationary contacts, a movable contact member, a stepping pawl for moving said contact member in two 95 distinctly separate movements in different directions to engage said stationary contacts, means for determining the change-over from one character of movement to the other, holding means for maintaining said movable 100 contact member in advanced position, and a release magnet for releasing said holding means to restore the movable contact to its normal position.

4. In an automatic switch, stationary contacts, a movable contact member adapted to be moved in two distinctly separate movement into engagement with stationary contacts, a single step-by-step mechanism for transmitting the separate movements to said 110 movable contact member, an electrically operated escapement switch for controlling the changeover from one character of movement to the other, holding means for maintaining said movable contact member in its operated 115 position, and a release magnet for releasing said holding means and for returning said escapement switch to normal position.

5. In an automatic switch, a longitudinally movable rod, a contact member carried 120 by said rod and movable independently thereof, a toothed member normally connected with said rod and said contact member, step-by-step mechanism for operating said toothed member to move said rod, escapement controlled mechanism for moving said rod from engagement with said toothed member and into a locked position, a holding pawl co-operating with said toothed member, and electrically controlled means for dis- 130

engaging said holding pawl from said toothed member and returning said escapement controlled means to normal position to cause the restoration of said contact member to normal position.

6. In an automatic switch, stationary contacts, brushes coöperating therewith, a stepping pawl for advancing said brushes in two distinctly separate movements in differ-

ent directions, a single electromagnet for operating said pawl, means for holding said brushes in advanced position, and a magnet for releasing said holding means to restore the brushes to their normal position. 10

In witness whereof I hereunto subscribe 15 my name this 30th day of July A. D., 1917.

JOHN N. REYNOLDS.
